Augustus J. Storck, Jr.
ATTORNEY.

UNITED STATES PATENT OFFICE.

WILLIAM T. HEADLEY, OF PHILADELPHIA, PENNSYLVANIA.

RAILWAY CROSSING AND METHOD OF MAKING THE SAME.

Application filed August 4, 1921, Serial No. 489,637. Renewed March 20, 1922. Serial No. 545,344.

To all whom it may concern:

Be it known that I, WILLIAM T. HEADLEY, a citizen of the United States, residing at Philadelphia, in the county of Philadelphia and State of Pennsylvania, have invented new and useful Improvements in Railway Crossings and Methods of Making the Same, of which the following is a specification.

10 Railway crossings usually consist of planking which is expensive and neither safe nor satisfactory because not infrequently the planks are torn up by passing trains and because the planking is not tight and 15 admits water and dirt to the ballast which interferes with drainage for the ties and is otherwise obviously objectionable. Sometimes slabs of molded concrete or metal are employed instead of planks but they are 20 very expensive and require special machinery for their installation and in use they are apt to creep or shift from the proper positions. In cities where asphalt plants are available hot asphalt paving mixture has 25 been laid between the rails and directly on top of and in contact with the ballast, but aside from the requirement of a hot asphalt plant such crossings are brittle and are at best makeshifts of limited application and 30 doubtful utility.

The principal object of the present invention is to obviate the above mentioned defects and disadvantages and to provide a comparatively inexpensive railway crossing 35 that can be laid cold anywhere by common labor and without the use of any plant or special apparatus and which, when laid, is not brittle or friable and is durable and satisfactory from every point of view including, more especially the requirements 40 of a railway line.

The invention will be claimed at the end hereof but will be first described in connection with the embodiment of it selected for 45 illustration in the accompanying drawings which are a perspective view of a railway crossing constructed according to and embodying features of the invention.

In the drawings 1 is ballast providing 50 drainage and access for air. Stone of ballast size may well come up to within three inches, more or less, of the under side of the head of the rail 2, and it should be compressed thoroughly by tamping or rolling 55 especially under the flange of the rail. 3

is a binder course, and 4 a superposed wearing surface each consisting of stone and an asphaltic binder arranged on the ballast and adapted to shed water and provide the necessary resilience. The binder course can be 60 made by coating sufficient ballast stone to cover a depth of two inches, more or less, of the surface after compression by tamping or rolling. The wearing surface can be made by coating stone or gravel which will pass 65 through a one inch ring and be retained on a quarter inch ring. The wearing surface is tamped or rolled and is made solid against the rail. The material used in each case for coating the stone is an asphaltic binder 70 which can be applied cold and with which the stone is laid cold and sets cold. An emulsion of asphalt with water is an example of the coating and asphalt cut back with a suitable volatile solvent is another example. 75 5 are ties contacting with the ballast 1 for drainage and air and roofed by the binder course and wearing surface. The rails 2 are arranged on the ties and embedded in the binder and wearing courses and where an 80 electric signal system is employed they are provided with an insulating coating indicated at α which may consist of the same material as the asphaltic coating used for the stone. Flange ways 6 are provided in 85 the wearing surface and they may well be formed by the flanges of the wheels of a train passing before the wearing surface is set. A sealing coating of the same asphaltic material may be applied to the surface of the 90 flange ways. It may be remarked that the provision of the binder course 3 effects a saving in the use of asphaltic binder and affords a good bearing and prevents shifting.

The term asphaltic binder is used herein 95 in a broad sense and is meant to cover tars and other equivalent bituminous materials.

It will be obvious to those skilled in the art to which the invention relates that modifications may be made in details of construction and procedure without departing from the spirit of the invention which is not limited as to those matters or otherwise than as the prior art and the appended claims may require.

I claim:

1. A railway crossing comprising in combination ballast providing drainage and access for air, a binder course and a superposed wearing surface each consisting of 110

stone and an asphaltic binder and arranged on the ballast and adapted to shed water and provide necessary resilience and stability, ties contacting with the ballast for 5 drainage and air and roofed by the binder course and wearing surface, rails arranged on the ties and embedded in the binder and wearing courses, and flange ways provided in the wearing surface, substantially as described.

2. A railway crossing comprising in combination ballast providing drainage and access for air, a binder course and a superposed wearing surface each consisting of 15 stone and an asphaltic binder and arranged on the ballast and adapted to shed water and provide necessary resilience and stability, ties contacting with the ballast for drainage and air and roofed by the binder 20 course and wearing surface, rails arranged on the ties and embedded in the binder and wearing courses and provided with an insulating coating, and flange ways provided in the wearing surface and having a sealing 25 coating, substantially as described.

3. The method of making a railway crossing which consists in putting ballast under and in contact with the ties for drainage and air, applying an insulating coating to

the rails, superposing a cold binder course 30 of stone and asphaltic binder upon the ballast, superposing a cold wearing surface of stone and asphaltic binder upon the binder course and against the rails to roof the ties, making flange ways in the wearing surface 35 before it sets, and sealing the flange ways by coating them with a sealing compound, substantially as described.

4. The method of making a railway crossing which consists in putting ballast under 40 and in contact with the ties for drainage and air, superposing a cold binder course of stone and asphaltic binder upon the ballast, superposing a cold wearing surface of 45 stone and asphaltic binder upon the binder course and against the rails to roof the ties, and making flange ways in the wearing surface before it sets, substantially as described.

5. The method of making a railway crossing which consists in putting ballast under 50 and in contact with the ties for drainage and air, superposing a cold course of stone and asphaltic binder upon the ballast and against the rails to roof the ties, and making flange ways in the wearing surface before it sets, substantially as described.

WILLIAM T. HEADLEY.
